2 SHEETS-SHEET 2.

UNITED STATES PATENT OFFICE.

LOUIS ROSENBAUM, OF NEW YORK, N. Y.

SAD-IRON.

1,073,634.

Specification of Letters Patent. Patented Sept. 23, 1913.

Application filed January 30, 1913. Serial No. 745,196.

To all whom it may concern:

Be it known that I, LOUIS ROSENBAUM, a citizen of the United States, residing at the city of New York, borough of Manhattan, 5 State of New York, have invented a certain new and useful Improvement in Sad-Irons, of which the following is a specification, reference being had to the accompanying drawings, forming a part hereof, in which—
10 Figure 1 is a side elevational view of a sad-iron embodying my invention; Fig. 2 is a top plan view of the base casting of the same, the handle or upper casting being removed; Fig. 3 is a horizontal sectional 15 view on the line 3—3, Fig. 1; Fig. 4 is a vertical longitudinal sectional view of the base casting of my new iron, the handle or upper casting being shown in side elevation disconnected therefrom; Fig. 5 is a trans- 20 verse sectional view through my new iron on the line 5—5, Fig. 1; and Fig. 6 is a rear elevational view of my new sad iron.

This invention relates to a certain new and useful improvement in sad-irons and particularly to that class of sad-irons wherein a combustible fluid is used as the heating medium, the objects of my invention being to provide a sad-iron of the kind stated which is simple in construction, has but few 30 separate parts, and the parts of which may be readily and quickly assembled and easily, firmly, and positively secured operatively together, which may be cheaply and economically manufactured, which will not 35 easily get out of good working order, which is efficient in operation, and which is so constructed that the flame or heat from the ignited combustible fluid will be distributed over the base of the iron and the same there- 40 by evenly and uniformly heated throughout its area, and to improve generally upon sad-irons of the class mentioned.

With these and other objects in view, my invention resides in the novel construction of 45 the several parts of my new iron and in the novel arrangement and combination of the same, all as will hereinafter be described and afterward pointed out in the claims.

As shown in the accompanying drawings, 50 wherein like reference characters refer to like parts throughout the several views, my new sad iron comprises substantially and preferably but three separate parts or members—a lower or body portion or base casting, as I will call it, A, an upper or handle 55

portion casting, as it might be called, B, and a burner C. Lower or body portion casting A is preferably a metallic casting open at its top and comprising a bottom wall 1 of any suitable thickness, flat on its 60 outer or ironing surface, as at 1^a, preferably pointed at its forward end, as at 1^b, and having the shape in plan elevation of the usual iron, and side and rear walls 2 and 3, respectively, projecting upwardly from 65 bottom of wall 1 and extending together continuously therearound. Side wall 2 integrally comprises, as shown particularly in Fig. 5, a portion 2^a projecting preferably and approximately perpendicularly up- 70 wardly from the outer edge of bottom wall 1 and a portion 2^b extending upwardly, and somewhat obliquely inwardly, from portion 2^a, wall 2 at the point of connection between portions 2^a and 2^b preferably curving in- 75 wardly, as shown at 2^c, and being provided with a series of slotted or elongated open- 80 ings 2^d. Along its upper edge wall 2 is preferably scalloped or cut away as shown, to provide a series or a plurality of substan- 85 tially U-shaped openings 4.

Cast integrally within member A approxi- 90 mately at the base of portion 2^b of side wall 2, see particularly Fig. 5, is a flat horizon- 95 tally-disposed wall 5 preferably cut away or 100 divided centrally and longitudinally, as at 5^a, into portions 6 and 7 which extend longitudi- 105 nally in casting A from rear wall 3 to a point slightly rearwardly of point 1^b, as shown particularly in Fig. 2. Cast integrally 110 with casting A and lying between, and connected to, said portions 6 and 7 of wall 5 and bottom wall 1 are separated series of thickened vertically-disposed webs 8—8, shown particularly in Fig. 3. The webs of 115 each of said respective series terminate at their inner surface preferably flush with the inner edges of flat wall portions 6 and 7; the outer surface of the webs of each of 120 said series is on a line preferably some dis- 125 tance inwardly from the inner surface of side wall 2 and preferably concentric therewith, whereby a continuous air channel, as 130 at 9, communicating at its ends with the exterior through suitable openings 9^a in rear 135 wall 3, is provided interiorly around casting A along the greater part of portion 2^a of side wall 2. Leading from said air passage 140 or channel 9 inwardly toward the longi- 145 tudinal central channel or space 5^a between 150

said series of webs and said horizontal wall portions 6 and 7, which channel at its rear end also communicates with the exterior through a suitable opening 5^b in rear wall 3, are air passages or channels 10 formed by, and between, said webs 8, each of said channels 10 being in alignment preferably with one of said elongated or slotted openings 2^a, which lead from the exterior into 10 said channel or passage 9. Rear wall 3 is also preferably provided above the level or plane of wall 5 with a plurality of outlet openings 3^a.

Upper casting B comprises a handle plate 11 adapted to extend completely over and close the top of base casting A and to be supported by, and to rest upon the upper edge of, side wall 2, as shown particularly in Fig. 1. Extending upwardly from opposite ends 20 of handle-plate 11 are similar handle-arms 12, the upper ends of these arms being preferably enlarged, as at 12^a, for receiving a suitable preferably wooden handle 13 and also suitably perforated for receiving and 25 holding a through-bolt 14 for securing said handle 13 firmly in position. Integral with handle-plate 11 and depending therefrom adjacent its rear end, is a rearwardly curved and projecting lug or locking member 15 adapted, when castings A and B are to be 30 assembled and operatively connected, to be inserted into and removably fit in a coöperating elongated slotted opening 16 in rear wall 3 of base A. At its forward end or 35 point handle-plate 11 is provided with a short longitudinal slot adapted to fit the base of a bent locking-member 17 threaded or otherwise pivoted in and upstanding from a thickened portion 18 within and at 40 the forward point of casting A, as shown in Fig. 4, this member 17 being swung to one side of a longitudinal position relatively to base A to releasably engage with handle-plate 11 and thereby at their forward end 45 lock castings A and B operatively together.

Burner C is preferably an elongated tubular member bent, as at 19, to provide a portion 20 provided at its open end with a suitable mixing chamber 21 (for purposes 50 well understood) and adapted to receive the end of a combustible fuel supply pipe (not shown); and a burner portion proper 22. Burner portion 22 fits through a suitable central opening in, and is supported at its 55 rear by, rear wall 3 of base A and extends longitudinally and centrally within base A above said central channel 5^a to forward point 1^b thereof, where it fits in a suitable circular recess 18^a in, and is closed 60 and supported at its forward end by, said thickened portion 18 of base A, this burner portion 22 being provided on its under surface with obliquely downwardly and outwardly disposed series of jet perforations 65 22^a and a centrally-disposed jet opening 22^b

at its forward end. By means of a set screw or the like 23 seated in a lug 3^b integral with, and projecting inwardly from, rear wall 3 of base A, burner C is releasably, but firmly, held in operative position in 70 base A. Preferably burner C is locked in base A by screw 23 in such position that, as shown, portion 21 thereof will project obliquely upwardly and thus be out of the way of the work being operated upon and 75 also of the hand or arm of the operator.

In operatively assembling castings A and B, casting B is placed upon casting A, lug 15 fitted into its slot 16, and locking member 17, which is now extending longitudinally of 80 base A or in the position thereof shown in Fig. 2, engaged by forwardly slotted handle-plate 11. Locking member 17 is now swung to one side of said longitudinal position and plate 11 engaged thereby, whereupon castings A and B will be at front and rear firmly and positively, though detachably, held or secured operatively together. The flame of the ignited combustible fluid supplied to burner C and issuing from said 90 series of jet openings 22^a and said central perforations 22^b is directed downwardly and outwardly from burner 20 directly upon said portions 6 and 7 of wall 5 and point 1^b of bottom wall 1. Said series of openings 95 2^a, together with said air passages or channels 5^a, 9, and 10, provide means for a plentiful supply of air to support combustion, and said outlet openings 4 with said openings 3^a provide escape passages to the exterior for 100 the products of combustion arising from within base A. Webs 8 will, in the movement of the iron while in use, tend to direct the air entering the air passages or channels 5^a, 9, and 10 forwardly within the area of 105 side wall 2 and out through said escape or outlet openings 4 and 3^a. The portions 6 and 7 of wall 5, while heated directly by the flame of the combustible fluid from burner 22, will prevent the jets or flame of the ignited combustible fluid coming directly in contact with bottom wall 1, the heat therefrom being directly radiated or transmitted through webs 8 and portion 2^a of wall 2 to, and the circulation of air within base casting A tending to evenly and uniformly distribute the heat over, bottom or ironing 110 wall 1.

I have found my new iron to be highly efficient in operation, and from the foregoing 120 it will be seen that my new iron comprises but few separate parts, and that said parts may be quickly and easily operatively assembled and secured together, and it should be understood that minor changes in the construction, arrangement, and combination of 125 the parts of my new iron may be made and substituted for those herein shown and described without departing from the nature and principle of my invention.

Having thus described my invention, what I claim and desire to secure by Letters Patent is:

1. A gas iron base or body portion comprising a hollow casting provided interiorly with a longitudinally cut-away or divided horizontally-disposed wall above and spaced away from its bottom wall, and series of vertically-disposed separated webs lying between, and connected to, said horizontally-disposed wall portions and said bottom wall, said webs terminating at their inner faces substantially flush with the inner edges of said wall portions and providing a central longitudinal channel in said base casting and at their outer faces being spaced inwardly from, and providing a channel around, the side wall of said base casting, the walls of said base casting being provided with openings leading into said channels; substantially as described.

2. A gas iron base or body portion comprising a hollow casting provided interiorly with a longitudinally cut-away or divided horizontally-disposed wall above and spaced away from its bottom wall, and series of vertically-disposed separated webs lying between, and connected to, said horizontally-disposed wall portions and said bottom wall, said webs terminating at their inner faces substantially flush with the inner edges of said wall portions and providing a central longitudinal channel in said base casting and at their outer faces being spaced inwardly from, and providing an outer channel around, the side wall of said base casting, the spaces between the webs of said series providing channels communicating with said longitudinal and outer channels and the walls of said base casting being provided with openings leading into said longitudinal and outer channels; substantially as described.

3. A gas iron base or body portion comprising a hollow casting provided interiorly with a longitudinally cut-away or divided horizontally-disposed wall above and spaced away from its bottom wall, and series of vertically-disposed separated webs lying between, and connected to, said horizontally-disposed wall portions and said bottom wall, said webs terminating at their inner faces substantially flush with the inner edges of said wall portions and providing a central longitudinal channel in said base casting and at their outer faces being spaced inwardly from, and providing an outer channel around, the side wall of said base casting, the spaces between the webs of said series providing channels communicating with said longitudinal and outer channels and the walls of said base casting being provided with a plurality of air-inlet openings leading from the exterior of the casting into said longitudinal and outer channels and above

the plane of said horizontally-disposed wall with outlet openings leading to the exterior of the casting; substantially as described.

4. A gas iron base or body portion comprising a hollow casting provided interiorly with a longitudinally cut-away or divided horizontally-disposed wall above and spaced away from its bottom wall, and series of vertically-disposed separated webs lying between, and connected to, said horizontally-disposed wall portions and said bottom wall, said webs terminating at their inner faces substantially flush with the inner edges of said wall portions and providing a central longitudinal channel in said base casting and at their outer faces being spaced inwardly from, and providing an outer channel around, the side wall of said base casting, the spaces between the webs of said series providing channels communicating with said longitudinal and outer channels and the walls of said base casting being provided with a plurality of air-inlet openings leading from the exterior of the casting into said longitudinal and outer channels and above the plane of said horizontally-disposed wall with outlet openings leading to the exterior of the casting, and a burner extending longitudinally within said base casting above said longitudinal channel, said burner being provided in its under portion with a plurality of jet openings; substantially as described.

5. A gas iron comprising a hollow base casting provided interiorly with a longitudinally cut-away or divided horizontally-disposed wall above and spaced away from its bottom wall and series of vertically-disposed separated webs lying between, and connected to, said horizontally-disposed wall portions and said bottom wall, said webs terminating at their inner faces substantially flush with the inner edges of said wall portions and providing a central longitudinal channel in said base casting and at their outer faces being spaced inwardly from, and providing a channel around, the side wall of said base casting, the walls of said base casting being provided with openings leading into said longitudinal and outer channels, an upper casting having a handle-plate fitting on said base casting, and a burner extending longitudinally within said casting above said longitudinal channel, said burner being provided in its under portion with a plurality of jet openings; substantially as described.

6. A gas iron comprising a hollow base casting provided interiorly with a longitudinally cut-away or divided horizontally-disposed wall above and spaced away from its bottom wall and series of vertically-disposed separated webs lying between, and connected to, said horizontally-disposed wall portions and said bottom wall, said webs terminating

at their inner faces substantially flush with the inner edges of said wall portions and providing a central longitudinal channel in said base casting and at their outer faces being spaced inwardly from, and providing an outer channel around, the side wall of said base casting, the spaces between the webs of said series providing channels communicating with said longitudinal and outer channels and the rear and side walls of said base casting being provided with a plurality of air-inlet openings leading from the exterior of the casting into said longitudinal and outer channels respectively, and above the plane of said horizontally-disposed wall with outlet openings leading to the exterior of the casting, an upper casting having a handle-plate fitting on said base casting, and a burner extending longitudinally within said casting above said longitudinal channel, said burner being provided in its under portion with a plurality of jet openings; substantially as described.

7. A gas iron comprising a hollow base casting provided interiorly with a longitudinally cut-away or divided horizontally-disposed wall above and spaced away from its bottom wall and series of vertically-disposed separated webs lying between, and connected to, said horizontally-disposed wall portions and said bottom wall, said webs terminating at their inner faces substantially flush with the inner edges of said wall

portions and providing a central longitudinal channel in said base casting and at their outer faces being spaced inwardly from, and providing an outer channel around, the side wall of said base casting, the spaces between the webs of said series providing channels communicating with said longitudinal and outer channels and the rear and side walls of said base casting being provided with a plurality of air-inlet openings leading from the exterior of the casting into said longitudinal and outer channels respectively, and above the plane of said horizontally-disposed wall with outlet openings leading to the exterior of the casting, an upper casting having a handle-plate fitting on said base casting, and a burner extending longitudinally within said casting above said longitudinal channel, said burner being provided in its under portion with a plurality of jet openings; substantially as described.

In testimony whereof, I have signed my name to this specification, in the presence of two subscribing witnesses.

LOUIS ROSENBAUM.
